UNITED STATES PATENT OFFICE

2,595,968

MANUFACTURE OF ICE

Lloyd L. McCoy, St. Louis, Mo., assignor to Ball
Ice Machine Co., St. Louis, Mo., a corporation
of Missouri

Application February 19, 1948, Serial No. 9,529

4 Claims. (Cl. 62—106)

1

The present invention relates to the manufacture of ice.

In the manufacture of ice, one of the problems is the possibility of freezing air bubbles into the blocks of ice that are ultimately produced by the ice making machine. In domestic ice machines, this problem has not been solved. In commercial machines, it has been attacked by flowing air through the water in the ice cans during the freezing operation. The purpose of this flow of air is to agitate the water, during the freezing operation, sufficiently to permit the air bubbles to escape, which they will do to a major extent by passing out of the top of the cans.

The foregoing system has disadvantages that are obvious, and it is a broad object of this invention to overcome these disadvantages.

The present invention has an object to agitate the water within the cans by a means that may be external to the cans, and that, in any case, does not require the introduction of a gaseous medium into the water for liquid being frozen.

More particularly, it is an object of the invention to employ ultrasonic vibrators to impart ultrasonic waves to the liquid in the water cans of the ice machine, and thereby vibrate the water in suchwise as to cause expulsion of absorbed air.

The drawing represents a more or less schematic section of a commercial ice machine embodying the present invention.

While the specification to follow refers to a type of commercial ice machine, it will be evident that the invention is applicable to other commercial types, and to domestic types.

The machine, as diagrammatically illustrated, has an outer tank 10 that is adapted to contain brine B. The brine tank may be provided with the usual drain line 11.

The tank has a plurality of longitudinally disposed beams 12, 13, 14, 15 and 16 that are designed to support the ice cans 17, of which four are shown solely to illustrate the present invention. The usual ice machine has many more. The adjacent pairs of beams, such as the beams 13 and 14, are grooved lengthwise to provide facing ledges that will support flanges at the top of the several ice cans. By this arrangement, the cans 17 may be inserted from the top of the tank 10 and will be supported by their upper flanges. The outside beams 12 and 16 are usually slightly spaced inwardly from the walls of the tank 10, although this arrangement is subject to wide variation in the ice industry.

2

In order to introduce air into the ice cans, the alternate beams, such as the beams 13 and 15, carry air conduits 20 and 21. These are normally fed from an air source 22 that leads from a compressor to a header from which the several pipes 20 and 21 emanate. Each can is provided with a branch pipe 23 or 24, as the case may be, these branch pipes leading from the main pipes 20 and 21 on opposite sides thereof. A suitable coupling 25 is provided at the top of each can 17, and an extension 26 depends from this coupling into the cans. The coupling permits the cans to be removed after the water within them has been frozen.

The illustrated type of ice machine includes a valved refrigerant inlet pipe 30 that leads to a plurality of coils 32 immersed within the brine B adjacent the several cans 17. An outlet refrigerant line 31 conducts the refrigerant out from the tank 10. It will be understood that a suitable refrigerating machine is attached to the two lines 30 and 31 in one of the conventional manners.

Lids 33 and 34 are employed to cover the top of the cans in the usual manner.

The foregoing ice machine is merely intended to be illustrative of a commercial ice producing plant. Of course, the sectional view shows only one row of cans, but it will be understood that there are a plurality of rows behind and in front of the row illustrated.

In the conventional ice machine, the cans 17 are filled with water, and, when the ice machine is running, the refrigerant passing through the coils 32 cools the brine that surrounds the cans. The water within the cans is thereby caused to freeze. However, the air within the several cans 17 tends to form into small bubbles that will cloud the ice unless suitable means are employed to eliminate this air. The conventional means is to bubble air through the water as the freezing takes place to agitate the water. Such agitation causes the air to escape from the top of the cans 17.

The disadvantages of such a system of agitation are obvious, and the present invention is designed to overcome them.

The vibration of the water by ultrasonic waves eliminates the air and settles out impurities toward the center and ultimately the top of the ice blocks within the cans 17, without the use of air. One or more such vibrators may be used. One of the vibrators is shown at 40 mounted in the wall of the tank 10, so that it will vibrate through the brine, and ultimately

3

to the water. These high frequency vibrations are thus imparted to the water in the cans 17 through the medium of the brine. Another vibrator 41 is shown as applied to the pipe 22 that leads into the air lines, and ultimately will transmit the vibrations through the air line connections into the water, so that the vibrator may be used as an adjunct to the air if desired. However, it is preferable to eliminate the air entirely, so that the vibrator 41 attached to these lines illustrates the introduction of the ultrasonic vibrations into the water by a direct conducting medium. In other words, where the ultrasonic vibrator 41 is employed, the air lines are not used as air lines, but merely as conductors entering the water itself.

A third vibrator 42 is shown as applied to one of the refrigerant lines that leads to the coils 32. As illustrated, the vibrator 42 is applied to the refrigerant inlet line 30. This causes conduction of the ultrasonic waves to the coils 32, and thence ultimately through the brine and the cans 17 to the water within them.

The foregoing use of one or more ultrasonic vibrators thus eliminates the necessity of passing the air through the water, or eliminates the necessity of employing other means to agitate the water in the cans 17 to prevent the production of white ice by the entrainment of air particles. It does so without the use of internal moving parts, and it affords external control for regulating frequency and intensity to suit the conditions, as they may vary in any particular machine at any time. It also is faster in its action, because the very high number of vibrations per second tends to cause the air to be expelled rapidly, and thereafter the freezing can take place without the air being present.

It will be understood that the drawing of the ice machine is illustrative. There are a number of other commercial types of ice machines, but they all, along with domestic refrigerators, employ cans or equivalent containers for the manufacture of ice, and they all employ mediums such as those illustrated through which the ultrasonic vibrations can be conducted to the water. The dispositions of the vibrators is illustrative, as the waves may be transmitted through any conducting medium to the water in the cans. The direct conduction is typified by the vibrator 41, but it will be understood that this vibrator

5

4

could be mounted on other parts, such as the cans themselves, or the can grids, or baskets frequently used to permit group handling of the cans. The vibrator 40 illustrates a preferred location, but it could be above the water line, in which case initially the waves would pass through air.

What is claimed is:

1. In a method of manufacturing ice, the steps of subjecting liquid in a container to a freezing medium to freeze the same, applying ultrasonic vibrations to the liquid during the freezing operation and penetrating the liquid with the vibrations as the liquid freezes.

2. In a method of manufacturing ice, the steps of immersing a container of liquid to be frozen into a bath of refrigerating liquid in a tank, applying ultrasonic vibrations to the refrigerating liquid in the tank during the freezing of the liquid to be frozen.

20
25
30
35

3. In a method of making ice, the steps of immersing a can of liquid to be frozen into a refrigerating medium, to freeze the liquid, introducing a vibration conductor into the liquid to be frozen, and applying ultrasonic vibrations to the conductor and thereby causing them to be transmitted to the liquid to be frozen.

4. In a method of making ice, the steps of introducing a can of liquid to be frozen adjacent a coil of a refrigerating machine, applying ultrasonic vibrations to the coil, and thereby conducting them to the liquid to be frozen.
